UNITED STATES PATENT OFFICE.

GEORGE H. B. CANOLES, OF WHITE MARSH, MARYLAND.

SPEED-GEARING.

SPECIFICATION forming part of Letters Patent No. 651,296, dated June 5, 1900.

Application filed September 13, 1899. Serial No. 730,348. (No model.)

To all whom it may concern:

Be it known that I, GEORGE H. B. CANOLES, a citizen of the United States, residing at White Marsh, in the county of Baltimore and 5 State of Maryland, have invented a new and useful Speed-Gearing, of which the following is a specification.

This invention relates to driving mechanism for bicycles in general, and more particularly to speed-gearings; and it has for one object to provide a simple and effective means for multiplying the speed of rotation of the chain-sprocket with respect to the rotation of the crank-axle.

15 A further object of the invention is to provide a construction which may be applicable to the usual bicycle-frame and which will, moreover, be compact in its structure.

In the drawings forming a portion of this 20 specification and in which like numerals of reference indicate similar parts in both views, Figure 1 is a side elevation showing the application of the gearing to a bicycle-frame. Fig. 2 is a vertical section of Fig. 1, parts being shown in elevation.

Referring now to the drawings, 5 represents the seat-tube, while 6 and 7, respectively, represent the bottom bar and a tie-rod, these parts of a bicycle-frame being connected in the usual manner at the crank-hanger 8.

In the crank-hanger 8 and in suitable ball-bearings is journaled a sleeve 9, at one end of which is fixed a sprocket 10, the outer face 35 of which is provided with a hub 11, having an external gear 12 thereon. Within the sleeve 9 and having a ball-bearing connection 13 therewith is journaled a crank-shaft 14, upon which is fixed a gear-wheel 15, meshing with the 40 minor element 16 of a cone-gear comprising a major element 17, meshing with the gear 12. This cone-gear is rotatably mounted upon a shaft 18, having fixed relation to the bifurcations 19 and 20 of a bifurcated extension 21 of a bracket, the arms 22 and 23 of which are provided with collars 24 and 25, fitted upon and secured to the seat-tube and bottom bar of the bicycle-frame. The crank 45 shaft or axle 14 is provided with the usual cranks 26, and, as shown in Fig. 2, the toothed periphery 30 of the sprocket 10 lies over and encircles the gear 12, the outer face of the sprocket being dished for this purpose.

From the above description and upon reference to the drawings it will be seen that 55

rotation of the shaft 14 will correspondingly move the gear 15 to rotate the cone-gear in the opposite direction. The engagement of the element 17 with the gear 12 will rotate the latter in an opposite direction to the cone-gear, or, in other words, in the same direction with the crank-axle. The sprocket 10, being fixed to or formed integral with the gear 12, will thus be rotated in the proper direction. Furthermore, it will be seen that the diameter of the gear 15 is greatly in excess of that of the element 16, the diameter of which in turn is less than that of the element 17, so that the sprocket 10 will be rotated at a greater speed than will the shaft 14. Furthermore, it will be seen that the structure is compact, increasing the tread of the machine only very slightly, while the ball-bearings of the different parts reduce the friction to a minimum.

In practice the specific construction and arrangement shown can be varied, while any desired materials and proportions may be used for the various parts without departing from the spirit of the invention.

While the invention is shown as applied to a bicycle, it will of course be understood that it may be attached to a vehicle of any kind and for any purpose.

What I claim is—
The combination with a bicycle and the frame thereof, comprising a crank-hanger having a seat-tube and bottom bar connected therewith, of a sleeve rotatably mounted in the crank-hanger, a sprocket fixed to the 90 sleeve and having a hub provided with a gear, the periphery of the sprocket being projected outwardly to inclose the gear, a crank-shaft rotatably mounted in the sleeve and having a gear fixed thereto, a bracket including collars disposed upon the seat-tube and bottom bar, the bifurcated extension of the bracket projecting into the inclosure of the periphery of the sprocket, a shaft fixed to the bifurcations of the extension, and a 95 cone-gear journaled upon said shaft and engaging the gears of the sprocket and the crank-axle.

In testimony that I claim the foregoing as my own I have hereto affixed my signature in 105 the presence of two witnesses.

GEORGE H. B. CANOLES.
